LOCOMOTIVE STOKER

Edward Ryan, Chicago, Ill., assignor, by direct and mesne assignments, to The Standard Stoker Company, Incorporated, a corporation of Delaware

Application May 9, 1928. Serial No. 276,211

9 Claims. (Cl. 110—101)

This invention relates more particularly to locomotive stokers of the type in which a screw conveyor is employed to propel the coal through a conduit and into the fire-box. Previous stokers of this type have been open to the objection that the conduit entered the fire-box in such a manner as either to be in the way of the fireman or to reduce the grate area. One of the objects of my invention is to overcome this objection.

10 Prior stokers have also been constructed with a comparatively sharp turn in the conduit, as the result of which clogging was very likely to occur. One of the objects of the present invention is to obviate this difficulty, which object 15 has been attained by locating the main portion of the conduit in an inclined position, the end of the conduit near the engine being thus raised so that only a slight curvature is required in the portion of the conduit which connects the 20 main portion of the conduit with the fire-box.

Another objection inherent in certain prior stokers is that the fuel, or a considerable portion of it, is delivered to the combustion space in such fine particles that the draft carries much 25 of it to the stack before it can be properly utilized. The present invention has overcome this difficulty by providing a preliminary crusher which reduces large lumps of coal and an auxiliary crusher which further reduces the coal to 30 the desired degree of fineness, the slight curvature of the discharge portion of the conduit preventing any substantial further reduction in size through excessive friction or pressure.

In stokers of the screw conveyor type it is 35 inevitable that the screw will deliver more coal at one side of the conduit than at the other. In previous types of stokers mechanism has been provided for distributing the fuel from the discharge end of the conduit onto the grate, but 40 owing to the fact that more of the coal was discharged at one side of the conduit than at the other the distributing means did not produce a fuel bed of uniform thickness. One of the 45 objects of this invention is to provide a distributor which may be manually adjusted into such position as to compensate for the fact that more coal is delivered at one side of the conduit than at the other, thus effecting a uniform distribution of the fuel onto the grate.

50 In prior stokers, the conveyor has been driven by means of an engine mounted on the engine unit of the locomotive and connected to the rear end of the conveyor on the tender through a line of shafting containing several universal joints. Such joints being a frequent source of trouble, I have done away with drives of this type, and have provided a prime mover which is located where the power is to be applied, namely, at the rear end of the conveyor.

55 A further object of the invention is to pro-

vide a fuel-tight flexible connection between the bottom of the fuel bin and the conveyor casing.

Further objects and advantages will become apparent from the following description taken in connection with the accompanying drawing 65 in which:

Fig. 1 is an elevational view partly in section through the fuel bin, the stoking mechanism and the rear part of the fire box, of the tender and locomotive.

70 Fig. 2 is a vertical section through the fuel bin and conveyor casing along the line 2—2 of Fig. 1.

Fig. 3 is a horizontal section along the line 3—3 of Fig. 1.

75 Fig. 4 is an enlarged fragmental section of the discharge conduit entering the rear wall of the fire box.

Fig. 5 is a fragmentary plan view along the line 5—5 of Fig. 4.

80 Fig. 6 is an enlarged fragmental horizontal section through the adjustable crusher.

Fig. 7 is a transverse section along the line 7—7 of Fig. 6.

85 While I have shown in the drawing and will herein describe in detail the preferred embodiment of the invention, it is to be understood that I do not intend thereby to limit the invention to the specific form disclosed, but aim to cover all modifications and alternative constructions falling within the spirit and scope of the invention 90 as expressed in the appended claims.

As illustrated in the drawing (Fig. 1) a tender 1 is shown coupled to a locomotive frame 2. A fuel bin 3 suitably mounted upon the tender is provided with a bottom having a discharge opening 4 therein adapted to be closed by a plurality of removable plates 2. A gate 6 is preferably provided in the front wall 7 of the bin to permit fuel to be deposited on a manual shoveling deck 8. 8^a is the locomotive deck on which the fireman stands while performing his duties. The locomotive is provided with a fire box 9 into which fuel from the bin 3 is to be fed.

95 To feed the fuel from the discharge opening 4 when one or more of the plates 5 are removed and into the fire box of the locomotive and to prepare the fuel for burning, I employ a screw 10 rotatably mounted within a conduit or casing 11 which casing forms the rearward part of a sectional feed conduit and at its rear end is provided with 100 an upstanding chute portion 12 and is supported from the bin structure. Preferably a rectangularly apertured discharge spout 13 (Figs. 1 and 2) surrounds the discharge opening 4 and enters into a rectangular slide ring 14. The slide ring 110 has a flange 15 extending outwardly from its lower edge, which flange slides on the upper surface 16 of the chute portion 12 and is resiliently pressed downwardly into engagement with the 115 surface 16 by means of expansive springs 17 posi-

tioned between the flange 15 and the bottom of the bin.

The casing 11 has a pair of laterally extending brackets 18 (Fig. 2) by means of which it is supported at its rear end. A pair of bolts 19 pass through apertures in the brackets 18 and upwardly therefrom and are preferably provided with spherical heads 20 at their upper ends arranged to cooperate with spherically formed seats in laterally extending brackets 21 on the bin structure to provide a swivel support for the casing. Similarly, nuts 19^a on the lower ends of the bolts are spherically formed and engage correspondingly shaped seats in the brackets 18. This swivel supporting means together with the telescopic and sliding connection provided between the chute 12 and discharge spout 13 provides a flexible connection between the casing and bin forming in effect a fuel-tight joint even when the tender moves relatively to the locomotive due to unevenness or curves in the road bed.

The casing or conduit 11 is inclined upwardly from its rear portion to its forward end 11^a, the latter being slightly curved upwardly; and at its forward end the casing is connected through a swivel or ball joint connection 22 with a discharge curved conduit 23 which extends into the fire box 9 through an opening 24 in the rear wall 25 thereof, of which opening is positioned above the mud ring 25^a. It will be apparent that by inclining the casing 11 upwardly from beneath the bin and having the conduit 23 enter the fire box above the mud ring the curved end portion 11^a and the conduit 23 may be formed so that its longitudinal axis is curved upon a large radius particularly adapted to prevent jamming of the fuel in the conduit 23 as it is pushed upwardly therethrough by the fuel which is still in engagement with the screw 10. As shown in the drawing, the discharge conduit is curved continuously upward, there being no reverse curve to cause jamming of the fuel. The conduit 23 preferably has a flange 24^a formed integrally therewith which flange abuts the outer surface of the fire box wall 25 and may be secured thereto by suitable clamping bolts 26 (Fig. 5). Thus the conduit 23 is rigidly secured to the fire box of the locomotive and by means of the ball joint 22 effectively supports the forward end of the casing 11.

As illustrated herein a prime mover comprising an engine 27 (Fig. 1) is mounted on a supporting bracket 28 rigidly secured to the rear end of the casing and is suitably connected to the shaft of the screw by means of enclosed gearing 29 and an aligned drive and driven shafts 60 and 61 respectively connected by a coupling member 62 which may be a flexible coupling member if preferred. In order that there need be no rigid connections between the rear end of the casing and the tender which would prevent the free movement of the swivel mounting for the casing and the flexible fuel-tight connection with the bin, the screw shaft is preferably provided with an extension 30 from which a lubricating system for the engine may be driven.

In order that the fuel fed into the fire box shall be of the proper size for efficient combustion the invention provides a preliminary crusher 31 within the casing 11 adjacent the forward end of the chute 12 and an auxiliary adjustable crusher 32 positioned in the casing 11 between the preliminary crusher 31 and the conduit 23. As illustrated herein the casing 11 is preferably provided with side pockets adjacent the receiving ends of the crushers so as to prevent lumps of fuel pass-

ing directly through with the screw. Thus before reaching the preliminary crusher a large lump would partially enter the pocket 33 (Fig. 3) and be broken, the fragments being further reduced as they pass the crushing ribs 31. The adjustable crusher has a pocket 34 (Figs. 6 and 7), the wall of which has crushing ribs. The pocket 34 is preferably formed in a member 35 which is adjustable transversely of the casing 11 in an aperture 36 formed therein. The casing at this point is provided with a flange 37 surrounding the aperture and has a pair of lugs 38 projecting from the opposite ends of the flange arranged to receive bolts 39. The member 35 has similarly projecting lugs 40 so that by placing a shim 41 between the lugs or varying the thickness of such a shim, the position of the member 35 relative to the screw may be adjusted to determine the size of the lumps of fuel fed into the conduit 23.

To distribute the fuel discharged from the upper end 23^a of the conduit a nozzle head 42 is provided. This nozzle head is preferably supported on a transversely adjustable slide 43 mounted on a rearwardly extending bracket portion 44 on the conduit and may be adjusted transversely of the conduit by means including a lever 45. The head 42 is preferably provided with side nozzles 46 and 47 (Fig. 5) and end nozzles 48, and at its rear end a steam chamber 49 is arranged to receive steam from a supply pipe 50 and discharge it into ports 51 which communicate with the nozzles. Valves 52 are adapted to regulate the flow of steam through the different nozzles.

To assist in the distribution of fuel from the conduit, a dividing rib or vane 53 is mounted on the nozzle head 42 in a position to extend downwardly into the conduit 23. This vane divides the fuel as it rises in the conduit and, being supported from the nozzle head, is adjustable transversely of the conduit to proportion the amount of fuel discharged on either side thereof. Thus if more fuel is being delivered at one side of the conduit 23 than at the other, or if the draft is greater on one side of the grate than on the other, or for any other reason the fuel burns more quickly on one side the head and vane may be adjusted transversely of the conduit to vary the distribution so as to obtain a uniform thickness on the grate.

An important feature of the apparatus is the provision of a means to cool the conduit 23 within the fire box so as to prevent destruction thereof due to the intense heat. As illustrated herein, this means comprises an external wall or jacket 54 cast integrally with the conduit and providing a water chamber 55 surrounding the conduit 130 within the fire box. The water may be fed into this chamber through a pipe 56 and out through a suitable pipe (not shown) on the opposite side.

It will be apparent from the foregoing that the novel construction disclosed herein embodies numerous advantageous features. By positioning the conveyor casing so that it is inclined upwardly and connecting it to a discharge conduit of large radius which extends into the fire box above the mud ring 25^a, the fuel passage becomes so nearly straight that the possibility of the fuel jamming in the casing or the discharge conduit is effectively prevented and fuel can be fed to the fire box of the boiler without reducing the grate area thereof and without taking up space on the deck 8^a on which the fireman needs to work. By making the conveyor a unitary structure and suspending it flexibly from the bin structure at its rear end, provision is made to compensate for any movement of the bin relatively to the loco-

5 motive and to permit the fuel-tight slide ring connection to function properly. The utility of the swivel suspension for the rear end of the casing and the telescopic connection with the fuel bin is augmented by mounting the discharge conduit rigidly on the fire box wall and inserting a ball or other swivel joint intermediate the front end of the casing 11 and the discharge conduit.

10 By supporting the prime mover or conveyor engine directly from the conveyor casing, the use of flexible or universal driving connections between the engine and conveyor are entirely eliminated.

15 It will also be apparent that by mounting the nozzle head for adjustment transversely of the conduit the distribution of fuel from the conduit may be varied and by embodying a dividing vane extending into the conduit, the adjustment feature of the distributing means is rendered more effective to maintain a uniform layer of fuel on 20 the grate under varying operating conditions. In mounting the nozzle head adjustably, it is also embodied in a unitary structure having a steam chamber and relatively short ports connecting the steam chamber with the nozzles.

25 The operation of the mechanism is further improved by providing both preliminary and auxiliary crushers for the fuel, the auxiliary crusher being adjustable to permit of varying the size of the fuel fed into the discharge conduit. These 30 and other features unite to provide a stoking mechanism which may be readily installed, is easily maintained and which is extremely efficient in operation.

I claim as my invention:

35 1. A locomotive stoker comprising, in combination, a fuel bin, a conveyor casing positioned beneath the fuel bin and extending forwardly therefrom, said casing being arranged to convey fuel for delivery to a locomotive firebox, conveying means within said casing, a prime mover supported from the casing for driving said means, a telescopic connection between the casing and the fuel bin and a swivel support for the rear end of the casing.

40 2. In a locomotive stoker, in combination, a fuel bin, a unitary fuel conveyor casing positioned beneath the fuel bin and extending forwardly therefrom, said casing being arranged to convey fuel for delivery to a locomotive firebox, a universal connection forming a support for the forward end of said casing, a flexible fuel-tight connection between the rear end of the casing and the discharge opening in the bin and means to support the rear end of the casing embodying 50 a pair of rods swivelly connected to the casing and to the bin structure.

45 3. A locomotive stoker comprising, in combination, a fuel bin, a conveyor casing positioned in part beneath the fuel bin and extending forwardly therefrom, said casing being arranged to convey fuel for delivery to a locomotive firebox, conveying means within said casing, a prime mover for driving said means supported by the rear end of the casing for movement therewith, and a flexible connection between the casing and the fuel bin for supporting the rear end of the casing and arranged to permit swiveling movement of the casing relatively to the bin in both vertical and horizontal planes.

55 70 4. The combination, with a locomotive firebox and a tender fuel bin, of a discharge conduit extending into the fire-box, a conveyor casing the rear end of which is yieldably mounted beneath the fuel bin and the forward end of

which is flexibly connected to the rear end of the discharge conduit, a conveyor within the casing, and a prime mover for the conveyor, said prime mover being attached to the rear end of the conveyor casing and thus mounted to move with the conveyor casing.

5 80 5. In a locomotive stoker, the combination of a fire-box, a conduit for discharging fuel into the fire-box, a nozzle head projecting over the upper end of said conduit, said head being bodily adjustable transversely of the conduit, and a dividing vane fixed to the head centrally thereof and projecting downwardly into the conduit.

10 85 6. A locomotive stoker comprising in combination, a fuel bin, a firebox having grates therein, a sectional fuel feeding conduit extending from beneath the fuel bin forwardly to the firebox and including a rearward casing section, a screw within said casing, an adjustable crusher comprising a recessed member adjustable transversely of the casing arranged to co-act with the screw to crush the fuel, and means adjacent the discharge end of the feeding conduit to distribute the fuel onto said grates.

15 90 7. In a locomotive tender having a deck, a locomotive stoker comprising, in combination, a fuel bin, a conveyor casing positioned beneath the fuel bin and extending forwardly therefrom, conveying means within said casing, gearing for said conveying means disposed at the rear of the casing, a supporting member rigidly mounted with said casing and extending rearwardly therefrom, a prime mover fixed on said supporting member below the tender deck for driving said conveyor means, said prime mover being 100 105 rearward of and spaced from the rearward end of the casing, and shafting including a coupling member connecting the prime mover with said gearing.

10 110 8. In a locomotive tender having a deck, a locomotive stoker comprising, in combination, a fuel bin, a conveyor casing positioned beneath the fuel bin and extending forwardly therefrom, a screw conveyor within said casing, gearing for said screw conveyor disposed at the rear of the casing, a supporting member rigidly mounted with said casing and extending rearwardly therefrom in a plane below the extended axis of said screw conveyor, a prime mover fixed on said supporting member below the tender deck for driving said screw conveyor, said prime mover being rearward of and spaced from the rearward end of the casing, and a coupling connection between the prime mover and the gearing.

115 120 9. In a locomotive tender having a deck, a locomotive stoker comprising, in combination, a fuel bin, conveyor casing positioned beneath the fuel bin and extending forwardly therefrom, conveying means within said casing, gearing for said conveying means disposed at the rear of the casing, a shaft for driving said conveying means through said gearing, a motor mounted below the tender deck rearwardly of said gearing having a power shaft for operating said gear drive shaft, said power shaft and said gear drive shaft being in substantial end to end alignment, and a supporting member for said motor rigidly mounted with said casing and extending rearwardly therefrom in a plane below the extended axis of said conveying means, said motor being rearward of and spaced from the rearward end of the casing.

125 130 135 140 145 EDWARD RYAN.
